(57) **CLAIM**

The ornamental design for a bicycle saddle with through-hole handle, as shown and described.

DESCRIPTION

FIG. 1 is a perspective view of a bicycle saddle with through-hole handle;

FIG. 2 is a bottom perspective view of the bicycle saddle with through-hole handle;

FIG. 3 is a top view of the bicycle saddle with through-hole handle;

FIG. 4 is a bottom view of the bicycle saddle with through-hole handle;

FIG. 5 is a front view of the bicycle saddle with through-hole handle;

FIG. 6 is a rear view of the bicycle saddle with through-hole handle;

FIG. 7 is a first side view of the bicycle saddle with through-hole handle; and,

FIG. 8 is a second side view of the bicycle saddle with through-hole handle.

The broken lines in FIGS. 1, 2, 4-8 representing the rails and support structures underneath the bicycle saddle with through-hole handle, show the design as being used, and form no part of the claimed design. The broken lines in FIGS. 1, 3, representing a channel on the top surface of the bicycle saddle with through-hole handle, show the design as being used, and form no part of the claimed design.

1 Claim, 6 Drawing Sheets
